SWIMMING TRUNKS

Arthur R. Kneibler, Kenosha, Wis., assignor to
Coopers Incorporated, Kenosha, Wis., a corporation of Wisconsin

Application March 19, 1937, Serial No. 131,759

5 Claims. (Cl. 128—159)

This invention relates to swimming or bathing trunks particularly designed for men's use, although not restricted thereto.

The main objects of the invention are to provide swimming trunks which will be exceptionally comfortable to wear; to provide swimming trunks which will provide the wearer with desirable body support to thereby improve the posture of the wearer and to add attractiveness to the figure; to provide means for effectively maintaining the swimming trunks in proper position on the wearer; and in general, it is the object of the invention to provide improved swimming trunks.

15 Other objects and advantages will be understood by reference to the following specification and accompanying drawings (2 sheets), wherein swimming trunks embodying a selected form of construction is illustrated.

20 In the drawings:

Fig. 1 is a front elevation;

Fig. 2 is a central section through the garment illustrating the inside of the rear portion of the garment;

25 Fig. 3 is a section showing the inside of the front portion of the garment;

Figs. 4 and 5 are sections on the lines 4—4 and 5—5 respectively of Fig. 1;

30 Fig. 6 is an elevation of the material blank employed in forming an outer garment member; and

Fig. 7 is an exploded view, illustrating the various material sections employed in forming an inner garment member.

35 Referring now to the drawings, the swimming trunks herein contemplated embodies inner and outer garments, respectively designated 8 and 9 in their entireties.

The outer garment 8 is preferably made of 40 wool or other similar material which is preferred for swimming garments. The outer garment may be made in any desired manner, but in this instance it is preferred that it be made from a single blank of material such as shown in Fig. 6.

45 The blank of material there illustrated embodies a back part 10 and a front part 11 integrally connected by a crotch-forming part 12. The material blank shown in Fig. 6 is folded upon itself so as to align the opposite ends 13 and 14 thereof and the adjacent side edges of the overlapped blank portions are then stitched together, thereby to form outer trunks having leg openings substantially as illustrated in Fig. 1. Belt-retaining loops such as indicated at 15 may be 50 secured to the outer trunks at desirable places to

position a belt 16 which normally is employed for maintaining the garment on the wearer, but which in this garment is employed mainly for the purpose of providing an attractive finished appearance to the garment. Because of the construction of the inner garment about to be described, the belt 16 is not essential and may be omitted if desired. It is, however, preferred that a belt of color contrasting to the color of the outer trunks be employed largely as a matter of 10 attractive appearance. Also, if desired one of the belt loops 15 may be made in the form of a coin pocket as indicated.

The inner garment 9 comprises a waist portion 20 and a lower portion 21. The waist portion is 15 preferably made of two sections of relatively heavy and strong elastic webbing indicated at 21 and 22 in Fig. 7, the portion 21 constituting the front forming portion and the portion 22 constituting the rear forming portion. The portions 21 and 22 have their ends united so as to form a body-encircling band which is stretchable to conform to the wearer's body. It is preferred that the front portion 21 be made somewhat wider in its central portion as indicated so as to overlie the abdominal regions to thereby provide a desired abdominal supporting effect. The elastic elements 21 and 22 are preferably made of knitted material in which rubber or latex strands or threads are incorporated in the knitting process so as to extend lengthwise of the sections whereby the waist-encircling portion is adequately 30 resistant to stretching, so as to provide the said abdominal supporting effect.

The lower portion 21 of the inner trunks is also 35 preferably formed of knitted material which is elastic transversely of the direction of its wales, but relatively inelastic lengthwise of its wales. The said lower portion comprises a back forming section 23, front side forming sections 24 and 25 and a two-ply central front forming section 26. The inner edges 27, 28 of the respective front side sections 24 and 25 are stitched as indicated at 29 to the respectively adjacent edge portions of the two-ply central front section 26. The outer edges 29 of the side front sections 24 and 25 are 40 respectively stitched to the adjacent edges of the rear section 23 as indicated at 30 (Fig. 4). The lower edges of the central front section 26 and the rear section 23 are also stitched together as 45 indicated at 31 (Fig. 5). The continuous upper edge of the lower section formed by uniting the sections 23, 24, 25, and 26 as above explained, is then stitched as indicated at 32 to the lower edge of the waist portion 22 so that the waist 50

portion 20 and the lower portion 21 cooperate to form complete inner trunks having leg openings.

As indicated in Figs. 5 and 7, the central front section 26 is made somewhat longer than the corresponding portion of the back section so that the seam 31 uniting the lower ends of said sections is disposed somewhat rearwardly of the center portion of the crotch part of the garment, which is formed by the lower extensions of said central front section and back section. By so positioning the seam 31, the comfort characteristic of the garment is improved.

The inner trunks thus formed is placed within the outer trunks and the upper marginal portion 33 of the outer trunks is then turned inwardly and downwardly over the inside of the upper marginal portion of the waist portion of the inner trunks. The inwardly and downwardly turned marginal portion 33 is then secured in place by suitable stitching indicated at 34 which extends all the way around the garment and serves to permanently unite the inner and outer garments adjacent the upper edges of the waist portions thereof.

25 The stitching employed at the various seams indicated is preferably of the well-known type which will permit stretching of the material where required or desired, so as not to interfere with yielding of the garment to conform to the wearer's body.

Both the inner and outer trunks are preferably made of knitted material and in the outer garment it is desired that the wales of the knitted material extend substantially vertically of the garment.

40 The knitted material employed in making the inner trunks is preferably of a lighter weight cotton material and the sections used in forming the lower portion of the inner trunks are preferably so arranged that the wales thereof extend vertically of the garment. By so arranging the sections, it will be observed that the wales of material in the crotch forming portion of the inner trunks extend vertically or from front to back and substantially parallel with the adjacent inner portions of the edges of the leg openings. Hence, the inner portions of the leg opening edges are relatively inextensible. The wales of the material in the portions of the inner trunks adjacent the outer edge portions of the leg openings extend transversely of such edge portions, so that said outer edge portions are adapted to be stretched considerably. The leg openings in the inner garment especially are preferably made so that when 45 the garment is applied, the leg openings will be enlarged, the enlargement resulting in stretching mainly of the outer leg opening portions. To reinforce the said outer leg opening portions, elastic straps 35 embodying rubber strands are 50 associated with said outer leg opening portions, said straps being enclosed within edge bindings 36 and secured in place by stitching indicated at 37, which also serves to secure the said edge binding in place.

60 The inner trunks portions are preferably so shaped that the leg opening edges of the inner trunks approximately coincide and line up with the groins of the wearer. When the leg openings are enlarged, the leg elastics 35 serve to provide a definite and material stretching action on the crotch portion of the inner trunks between the leg openings, whereby the crotch portion is stretched both lengthwise and transversely so as to provide 65 a smooth, body-conforming fit.

70 The elastic waist portion of the inner garment

is made of such size that when the garment is worn, said waist portion will be stretched. Owing to its normal tendency to contract to its unstretched condition, the waist portion will adequately hold the bathing trunks in proper place on the wearer and also supply the desired abdominal supporting effect, the latter being somewhat enhanced by the centrally increased width of the front portion of said waist band. The snug fitting leg openings are also advantageous in that they effectively prevent exposure regardless of the posture of the wearer.

75 The inner trunks is designed to fit more or less snugly on the person, whereas the outer trunks, being less taut, smoothes out body contours and thereby produces the desired attractive appearance.

80 Changes in the described structure may be made without departing from the spirit of the invention, the scope of which should be determined by reference to the following claims, the same being construed as broadly as possible consistent with the state of the art.

I claim:

1. A swimming garment comprising outer 25 trunks, and relatively independent inner trunks of different material than said outer trunks, said outer and inner trunks having their waist portions united, said inner trunks having a wide waist portion of elastic material constituting an abdominal support and a lower portion of softer 30 material of less elasticity.

2. A swimming garment comprising outer trunks, and relatively independent inner trunks of different material than said outer trunks, said 35 outer and inner trunks having their waist portions united, said inner trunks having a wide waist portion of relatively strong, elastic material constituting an abdominal support, and a lower portion of softer less elastic material, said lower 40 portion having a body supporting crotch part of material which is elastic transversely and relatively inelastic longitudinally of the garment, said crotch part being secured to and thereby supported from said waist band.

3. A swimming garment comprising outer 45 trunks, and relatively independent inner trunks of different material than said outer trunks, said outer and inner trunks having their waist portions united, said inner trunks having a wide waist 50 portion of relatively strong, elastic material constituting an abdominal support, and a waist portion of softer less elastic material, said lower portion comprising a back part depending from the back of said waist portion and a front part 55 having a centrally disposed body supporting crotch section of material which is elastic transversely of the garment but relatively inelastic longitudinally thereof, said crotch section being secured at its front or upper end to the front of 60 said waist portion and having its lower or rear end secured to the lower end of said back part, the adjacent side edges of said front and back parts being united.

4. A swimming garment comprising outer 65 trunks, and relatively independent inner trunks of different material than said outer trunks, said outer and inner trunks having their waist portions united, said inner trunks having a wide waist portion of relatively strong, elastic material constituting an abdominal support, and a waist portion of softer less elastic material, said lower portion comprising a back part depending from the back of said waist portion and a front part having a 70 centrally disposed two-ply body supporting crotch 75

section of material which is elastic transversely of the garment but relatively inelastic longitudinally thereof, said crotch section being secured at its front or upper end to the front of said waist portion and having its lower or rear end secured to the lower end of said back part, the adjacent side edges of said front and back parts being united.

5. A swimming garment comprising outer trunks and relatively independent, inner trunks of different material than said outer trunks, said outer and inner trunks having their waist portions united, said inner trunks being sufficiently smaller than said outer trunks to permit the inner trunks 10 to lie smoothly within and be wholly concealed by the outer trunks, said inner trunks comprising a wide waist portion of relatively strong elastic material constituting an abdominal support, and a lower portion of soft, knitted material of less 15 elasticity than said waist portion, said lower portion comprising a back part depending from the back of said waist portion, and a front part hav-

ing a centrally disposed crotch section, said crotch section being secured at its front or upper end to the front of said waist portion and having its lower or rear end secured to the lower end of said back portion, the adjacent side edges of said front and back parts being united, the wales of the material in said crotch section and adjacent the inner portions of said leg openings formed by said crotch section extending substantially parallel with the inner leg opening edges, whereby the latter are relatively inextensible, the wales of the material in said front part adjacent the outer leg opening portions extending transversely of said outer leg opening portions, whereby the latter are resiliently extensible, and elastic elements associated with said leg openings and stretchable with said outer leg opening edge portions so as to tend to stretch said inner leg opening edge portions and the intermediate crotch portion to maintain a smooth, body-conforming and supporting fit in 20 the crotch portion of the garment.

ARTHUR R. KNEIBLER.
